UNITED STATES PATENT OFFICE.

CHARLES L. HOGUE, OF OAKLAND, CALIFORNIA.

HOOK FOR EYEGLASS CHAINS.

Application filed February 9, 1922. Serial No. 535,240.

To all whom it may concern:

Be it known that I, CHARLES L. HOGUE, a citizen of the United States, residing at Oakland, in the county of Alameda and 5 State of California, have invented certain new and useful Improvements in a Hook for Eyeglass Chains, of which the following is a specification.

My invention is an improved hook for 10 engaging the hair to prevent eye glasses from dropping.

Referring to the annexed drawing in which my invention is illustrated and which forms a part of this specification:

15 Figure 1 is a front view of a pair of eye glasses with my hook connected to the chain which is connected to one of the glasses.

Figure 2 is a front view of my hook.

My hook is made of a single piece of wire 20 bent in the middle into an eye 1, then twisted together from said eye into a twist 2, then bent into two spring arms 3 and 4, which arms are bent over each other at 5 and 6 then bent outwardly first at about 45° to the 25 axis of the hook and then at an angle so that they diverge outwardly slightly toward their ends, and then backwardly upon their forward sides into hook members 7 and 8. The eye 1 is connected by a ring 9 30 to one end of a chain 10, the other end of

said chain being connected by a ring 11 to one of the lenses 12 of a pair of eye glasses.

The arms 3 and 4 may be sprung inwardly and the hook members 7 and 8 brought together so that the hook may be easily inserted 35 into the hair. Upon releasing said arms the hook members are sprung outwardly and they catch firmly in the hair.

Having described my invention, I claim:

1. A hook comprising a single piece of 40 wire bent into an eye, spring arms extending from the eye, the upper ends of the spring arms being twisted in one direction and the arms being twisted together approximately in the middle in the opposite 45 direction, said arms diverting above and below the second twist, said arms terminating in U shaped hooks.

2. A hook comprising a single piece of wire bent into an eye, spring arms extending 50 from the eye, the upper ends of the spring arms being twisted in one direction and the arms being twisted together approximately in the middle in the opposite direction, said arms diverging above and below the second 55 twist, said arms terminating in U shaped hooks, said hooks lying in planes at right angles to the plane of the spring arms.

In testimony whereof I affix my signature.

CHARLES L. HOGUE.
